UNITED STATES PATENT OFFICE.

EDWIN PINKHAM, OF BALTIMORE, MARYLAND, ASSIGNOR OF ONE-HALF
TO GRAFTON LLOYD ROGERS AND HARRY ROGERS, BOTH OF SAME
PLACE.

CRINGLE-CLEW FOR SAILS.

SPECIFICATION forming part of Letters Patent No. 439,422, dated October 28, 1890.

Application filed June 4, 1889. Serial No. 313,066. (No model.)

To all whom it may concern:

Be it known that I, EDWIN PINKHAM, a citizen of the United States, residing at Baltimore city, in the State of Maryland, have invented a new and useful Improvement in Cringle-Clews for Sails, of which the following is a specification.

My invention relates to cringles for sails; and it consists in the improved construction and arrangement or combination of parts, hereinafter fully disclosed in the description, drawings, and claims.

The objects of my invention are, first, to provide improved means for securing cringles to the edges or corners of sails for the attachment of earings, clew-lines, hoops, or other articles of ship's rigging; second, to provide an improved cringle, which is secured to the bolt-rope and to a portion of the sail inside of the latter; third, to provide improved means for further securing said cringle, and, fourth, to provide improved means for preventing chafing of the bolt rope or fastenings at the cringle. These objects are attained in the cringle illustrated in the accompanying drawings, forming part of this specification, in which the same reference-numerals indicate the same parts, and in which—

Figure 1 represents a side view of a portion of a sail provided with my improved cringle; Fig. 2, a similar view showing the cringle applied in the corner of a sail to serve as a clew for the attachment of a clew-line; Fig. 3, a transverse section on the line $x-x$, Fig. 1, and Fig. 4 a side view, of a portion of a sail provided with my cringle, showing the chafing-piece removed; and Fig. 5 shows the ring-cingle formed with a projecting eye on its sail-fastened part.

In the drawings, the numeral 1 indicates the sail, the edge of which is bound in the usual manner with the bolt-rope 2. The cringle B is formed of a circular or oblong ring 4, of malleable metal or rope, which has at diametrically opposite points two eyes 5, formed at right angles to said ring. The cringle is secured to the sail by having the bolt-rope passed through its two eyes and by having the inner portion which overlaps the

sail secured to the same by seizings 6, which are passed over said portions and through small grommets 7 in the sail formed at both sides of overlapping portion. The outer free-eye portion of the cringle serves for the attachment of the earing if the cringle be used at the leech of a sail for the reefing earings; of the clew-line, if it be used for a clew, as shown in Fig. 2; of the hank or hoop, if it be used in the luff of the sail; of the sheets, if it be used in the heel or corner of a sail; of the down-haul, halyards, or any other portion of a ship's rigging, according to its location upon the sail. A key or flat bar 8 is preferably driven through the eyes of the cringle at the inner side of the bolt-rope and serves to stiffen said rope at the point of attachment of the cringle and to further secure and wedge or clamp the cringle to the bolt-rope. A chafing-piece 9 of canvas is preferably passed around the bolt-rope through the cringle and is secured by stitching or seizing to the sail, covering the inner portion of the cringle and the grommets and seizings, and said chafing-piece serves to protect the bolt-rope and the grommets and seizings from chafing wear against the portion of the rigging to which the cringle is attached.

It will be obvious that this style of cringle and its fastening will be more secure than the old-style cringle, in which a thimble was inserted through an eye formed by a strand of rope, spliced from two grommets in the sail, in which the sail was liable to be stripped entirely off the bolt-rope if a tear should occur at one of the grommets, and that my improved cringle is less liable to wear than the aforesaid old style, besides being easier applied.

My improved cringle will be less cumbersome and simpler in construction when used for a clew-eye than the old-style clew-eye, which consisted in a ring secured in two metal grommets or thimbles secured in the corner of the sail, in which said grommets or thimbles were very liable to work loose and rip the sail.

If the cringle is to be applied to an old sail, it may be made with split eyes, which may be passed over the bolt-rope and thereupon se-

cured, and even in this form it will be simpler to apply than a cringle composed of two halves and riveted upon the bolt-rope and sail, such as have heretofore been made.

5 My eyed cringle-clew can be attached to any cut of sail, and it may be formed with a laterally-projecting eye C on its part, which extends over and is fastened to the body of the sail inside of the bolt-rope for the attachment of a clew-line block for hauling or furling up square-cut sails, to the corner of which the device is applied.

Referring to the re-enforcing bar 8, it may be placed within the bolt-rope covering-sail.

15 Having thus fully described the construction and arrangement or combination of the several parts of my improved cringle, its use and advantages, what I claim as new is—

1. An improved cringle, which consists of 20 a ring having two opposite eyes formed in it and whose planes are at right angles to the plane of the ring, substantially as described.

2. In combination with a sail and its bolt-rope, a cringle consisting of a ring having 25 opposite eyes through which the bolt-rope passes and whose planes are at right angles to the plane of the ring and secured to the sail by the inner overlapping portion, substantially as described.

30 3. In combination with a sail and its bolt-rope, a cringle consisting of a ring having opposite eyes whose planes are at right angles to the plane of said ring and through which the bolt-rope passes, and having its inner 35 overlapping portion secured to the sail, and a key or bar inserted through said eyes and said bolt-rope, substantially as described.

4. In combination with a sail and its bolt-

rope, a cringle consisting of a ring having 40 opposite eyes whose planes are at right angles to the plane of said ring and through which the bolt-rope passes, and having its inner overlapping portion secured to the sail, and a chafing-piece inserted through said cringle and around said bolt-rope and having its ends 45 secured to the sail and covering the inner portion of said cringle, substantially as described.

5. In combination with a sail and its bolt-rope, a cringle consisting of a ring having 50 two opposite eyes whose planes are at right angles to the plane of said ring and through which the bolt-rope passes, and having its inner overlapping portion secured by seizings passed through grommets in the sail, a key or bar inserted through said eyes and against 55 the inner side of the bolt-rope, and a chafing-piece inserted through the outer portion of said cringle and around said bolt-rope and stitched to said sail to cover the inner portion of said cringle and its seizings, substantially 60 as described.

6. An improved cringle, which consists of a ring having two eyes formed in it diametrically opposite and whose planes are at right angles to the plane of the ring and a laterally-projecting eye formed at its sail-fastened 65 part, substantially as described, for the purpose specified.

In testimony whereof I have hereunto set my hand in the presence of two subscribing 70 witnesses.

EDWIN PINKHAM.
